UNITED STATES PATENT OFFICE.

LEWIS C. MORSE, OF GLOUCESTER, MASSACHUSETTS, ASSIGNOR TO RUSSIA CEMENT COMPANY, OF GLOUCESTER, MASSACHUSETTS, A CORPORATION OF MASSACHUSETTS.

LIQUID CONTAINER AND DISPENSER.

Application filed January 4, 1924. Serial No. 684,440.

To all whom it may concern:

Be it known that I, LEWIS C. MORSE, a citizen of the United States, residing at Gloucester, in the county of Essex and State 5 of Massachusetts, have invented new and useful Improvements in Liquid Containers and Dispensers, of which the following is a specification.

The invention is embodied in a container 10 for liquid, such as stamp pad ink, adapted to prevent a gravity flow of ink to a stamp pad when the container is inverted, and to permit a limited extrusion of ink when percussion, caused by tapping the outlet portion 15 of the inverted container against the pad, is exerted on the container.

The chief object is to enable an ink container to be manipulated to properly ink a stamp pad, without liability of wasting ink 20 and soiling the hands of the users.

Of the accompanying drawings forming a part of this specification,—

Figure 1 is a top plan view of a dispensing container embodying the invention. 25 Figure 2 is a section on line 2—2 of Figure 1. (Figures 1 and 2 show the preferred size of the orifices hereinafter referred to.)

Figure 3 is a view on a larger scale similar to a portion of Figure 2, showing the container inverted.

The same reference characters indicate the same parts in all of the figures.

In the drawings, 12 designates a receptacle which may be a glass bottle, having a 35 mouth 13. 14 designates a retaining head, secured to the mouth by the means hereinafter described, and provided with a plurality of small orifices 15, collectively constituting the sole outlet for ink 16 with which 40 the receptacle is charged.

The orifices are proportioned to receive fillings 17 of ink when the receptacle is inverted, and to retain said fillings by capillary action, so that they are prevented from dropping by gravity from the head, and are caused to prevent the entrance of air into the receptacle, so that the charge is supported in the inverted receptacle by atmospheric pressure. The orifices 15 are 45 preferably circular, and a suitable diameter of each is about one twenty-fourth of an 50 inch.

The orifices permit a limited extrusion of the fillings 17, when the receptacle is inverted and the head is tapped percussively 55 against a stamp pad, this action causing a slight downward movement of the charge.

The outer surface of the head 14 is exposed, so that it may be used as a spreader for the extruded ink, and as a seat for a 60 screw cap 20, applied to the mouth 13, and adapted to close the orifices 15 when the device is not in use.

The means for securing the head to the mouth 13, includes a flange 18, formed on 65 and projecting inward from the margin of the head, and a compressible packing member 19, preferably of cork, surrounding the flange and conforming to the internal surface of the mouth. The head and flange 70 are preferably of sheet metal and formed in one piece.

The outer end of the packing member 19 is preferably flush with the outer side of the head 14, and constitutes an enlargement 75 of the spreader and of the cap seat. Preferably, the outer end of the mouth 13 is flush with the outer end of the packing member and the outer surface of the head, so that the mouth end constitutes an additional enlargement of the spreader and of 80 the cap seat.

It is obvious that the described device 85 may be used for dispensing and spreading other liquids.

I claim:

1. A liquid container and dispenser comprising a receptacle, a retaining head of sheet material, provided with a plurality of relatively small orifices, and with an inwardly projecting flange, and a compressible packing surrounding said flange and conforming to the internal surface of the receptacle mouth, to receive the head and its flange, the outer end of said packing and the outer surface of said head being substantially flush with each other and collectively constituting a face adapted to spread liquid extruded through said perforations, and a seat for a closing cap engaged with 95 the receptacle.

2. A liquid container and dispenser comprising a receptacle, a retaining head of sheet material, provided with a plurality 100

of relatively small orifices, and with an inwardly projecting flange, and a compressible packing surrounding said flange and conforming to the internal surface of the receptacle mouth, to receive the head and its flange, the outer ends of said mouth and packing, and the outer surface of said head

being substantially flush with each other and collectively constituting a liquid-spreading face and a seat for a closing cap engaged with the receptacle. 10

In testimony whereof I have affixed my signature.

LEWIS C. MORSE.
